UNITED STATES PATENT OFFICE.

ARTHUR WILLARD BOSCH, OF EAST ORANGE, NEW JERSEY, ASSIGNOR
TO McCLEARY, WALLIN & CROUSE, OF AMSTERDAM, NEW YORK, A CORPORATION OF NEW YORK.

DESIGN FOR A RUG.

SPECIFICATION forming part of Design No. 37,013, dated June 28, 1904.

Application filed May 26, 1904. Serial No. 209,993. Term of patent 3½ years.

To all whom it may concern:

Be it known that I, ARTHUR WILLARD BOSCH, a citizen of the United States, residing at East Orange, county of Essex, State of New Jersey, have invented a new, original, and ornamental Design for Rugs, of which the following is a specification, reference being had to the accompanying drawing, forming a part thereof.

10 The single figure of the drawing is a plan view of a rug embodying said design.

What I claim as new, and desire to secure by Letters Patent, is—

The ornamental design for a rug substantially as herein shown.

ARTHUR WILLARD BOSCH.
